MACHINE FOR MAKING BATS OF FIBROUS MATERIAL

Patrick T. Jackson, Cambridge, Mass., assignor to
American Reinforced Paper Company, Attle-
boro, Mass., a corporation of Massachusetts

Application December 31, 1932, Serial No. 649,730

4 Claims. (Cl. 154—1)

This invention relates to bats of fibrous material and the machine for making them, and is more particularly concerned with the formation of composite bats in which the fibres of the bats are reinforced.

It is well known that fibrous material formed into a web or sheet has little or no resistance to rupture and even where such fibrous sheet is formed into a plurality of layers, it still has little or no strength or resistance to rupturing strains. This is observable in cases where the bat is employed in connection with springs in the formation of a mattress and in such cases the springs soon penetrate into the fibrous mass and render the mattress unserviceable.

In its broader aspect the present invention contemplates the formation of a bat of fibrous material so associated with reenforcing filaments that the composite bat, as a whole, shall possess inherent qualities of strength, durability, and resistance to disturbing strains, and the completed bat presents a substantially compact unit. The fibrous material composing the bat proper may be produced from any suitable fibre which can be carded or formed into a sheet or web, while the reenforcing filaments may be associated therewith in a variety of ways calculated to impart the desired strength and durability, as by incorporation within or on the sheet or web. Such reenforcing filaments may take various forms, but good practical results are secured by unspun fibres of relatively longer staple than the fibres composing the sheet or web although spun yarn, strings, or the like may be used.

In the present instance, the invention will be described in connection with a web or sheet of cotton fibre, as it comes from the garnet or similar machine, but as hereinbefore stated, such web or sheet may be composed of any fibre which lends itself to treatment by carding, garnet, or other operation in the production of a sheet or web of unspun fibre. Similarly, the reenforcing filaments will be described as of the unspun long staple type, which are taken from a source of supply and elongated or attenuated as they are delivered for incorporation with the fibrous sheet or web to be reinforced, but while this presents a good practical way of combining the reenforcing filaments to the sheet or web, the filaments may be previously prepared and delivered directly to the sheet or web from a roll or other supply.

The invention and novel features thereof will best be made clear from the following description and accompanying drawings of one practical means for carrying the invention into effect.

In the drawings:—

Fig. 1 is a perspective view of a machine containing the present invention;

Fig. 2 is a diagrammatic view showing the cot-

ton sheet and reenforcing fibres as they appear during the formation of the composite bat;

Fig. 3 shows a section, parts broken away, of a composite reinforced bat containing the present invention;

Fig. 4 is a diagrammatic plan view showing the overlapping relation of the elements composing the bat with parts broken away, to indicate that the reenforcing filaments in adjacent layers of the reinforcements extend at an angle to each other and substantially transversely of the longitudinal dimensions of the bat;

Fig. 5 is a diagrammatic view showing more particularly the relation of the reenforcing filaments or fibres and their application to the fibrous cotton sheet; and

Fig. 6 is a side elevation in diagrammatic form showing the receiving conveyor and the combined cotton sheet and reenforcing filaments being laid thereon.

The sheet or web of fibrous material may be produced in any of the well known machines for that purpose and in the present instance of the invention the sheet or web 1 is shown as being delivered from a garnet machine 2 and stripped from the delivering roll 3 of the garnet by the doffer 4. The sheet or fleecy web 1 as it comes from the garnet machine is delivered upon the endless belt 5 which is appropriately driven to carry the cotton sheet of fibrous material to a conveyor 6.

The conveyor 6 in the present instance consists of an endless belt passing around the rollers 7 and 8 and one of said rollers at least is driven to carry the fibrous sheet away from the belt 5 as it is delivered thereon.

Pivotedly mounted on an axis 9 is a camel back comprising the side frames 10 and 11 which are pivotally connected at their adjoining ends at 12 to permit the camel back to be moved in a path to form superposed layers of material as indicated in Figs. 1 and 5.

As a means for carrying the fibrous sheet and reinforce the reenforcing filaments, the camel back is provided with belts 13 and 14 which serve to feed the material and form superposed layers thereof as will further appear.

In accordance with the present invention the sheet or fleecy web is to be reinforced and strengthened by reenforcing filaments or fibres of long staple which are taken from a suitable source of supply either in the form of rovings or otherwise, as indicated at 15. The reenforcing filaments or fibres pass between the feed rolls 16 and 17 whereby the fibrous mass is moved in a direction towards the fibrous sheet to be reinforced.

It is desirable that the reenforcing filaments shall be drawn out or attenuated and as one means to this end the present invention provides

a series of comb bars 18 having teeth 19 and the reenforcing filaments are directed to the comb from the feed rolls 16 and 17 by a suitable guide 20 so that the teeth of the comb pass into the 5 mass of reenforcing filaments or fibres and carry them towards the cotton or other fibrous sheet.

As indicated in the present instance of the invention the comb bars 18 are mounted upon an endless belt 21 which passes about the rollers 22 10 and 23, one at least of which is driven to impart to the comb a traveling movement towards the sheet of cotton fibre.

Mounted above the roller 8 about which the belt 6 passes is a pressure roller 24 which receives 15 the reenforcing filaments or fibres as they are delivered from the comb, and in order that the reenforcing filaments or fibres may be attenuated or drawn out the rollers 8 and 24 rotate with a surface speed somewhat greater than the speed 20 of the comb, the effect being that while the comb teeth hold the reenforcing filaments and are moving such filaments towards the cotton sheet the filaments are attenuated or drawn out and thereupon delivered to the cotton sheet which 25 also passes between the rollers 8 and 24; thus the reenforcing filaments or attenuated fibres are delivered to the fibrous cotton sheet and both thereupon pass on to the belt 13 of the camel back which feeds the two as a unit above the top 30 of the camel back and on to the delivery belt 14 as illustrated in Figs. 1 and 5.

Extending between the rollers 25 and 26, Fig. 1, is the receiving conveyor 27 which in the present 35 instance of the invention is constituted as an endless belt, the upper run of which is given movement as indicated by the arrow, Fig. 1, by the driven roller 26. The rollers 25 and 26 may be appropriately supported upon the risers 28 and 29.

40 The camel back is operated as usual to impart to the delivery end portion thereof at 30 reciprocating movements back and forth over the receiving conveyor, with the result that the combined cotton sheet and reinforcements as a unit 45 are laid in layers, one upon the other, in the formation of the composite reenforced bat.

Inasmuch as the receiving conveyor 27 is moved longitudinally as the delivery end of the camel back lays the cotton sheet and reenforcing 50 filaments as a unit thereon, it follows that the thickness of the finished bat may be varied by changing the speed of the receiving conveyor 27 and moreover the reenforcing filaments or fibres 31 which have been applied to the cotton 55 sheet will assume an angular relation to each other on adjacent layers of the reinforcements.

This is illustrated in Fig. 4; wherein it will be noted that the reenforcing filaments or fibres 31 are angularly related in adjacent layers of 60 reinforcements and form substantially a diamond shaped relation with the reinforcements extended generally transversely to the longitudinal dimension of the bat.

65 It may be desirable in some instances to subject the bat to compression as it is delivered from the machine and this is indicated in Fig. 1 wherein the bat is delivered from the apron 27 and passes about a roller 32 and then between the 70 nip of that roller and a roller 33. From the roller 33 the bat is delivered under the compression roller 34 so that the finished bat is consolidated to any desired extent suitable for its intended use.

75 Having reference to Fig. 3 it will be noted that

the sheet 1 of cotton fibre and the reenforcing filaments 31 are laid back and forth in superposed layers with the result that the composite reenforced bat presents a strengthened condition by reason of the reinforcements between the 5 layers of the cotton sheet. A reinforced bat made in accordance with the present invention when used for mattress purposes, for instance, presents a cotton fibre structure which represents the elasticity desired and yet presents a strengthened and stabilized structure through which springs as commonly employed may not penetrate.

What is claimed is:—

1. In a machine for making a composite reenforced bat of fibrous material, the combination of a traveling conveyor for a soft fibrous sheet, feeding devices for feeding unspun reenforcing fibres of relatively long staple towards the fibrous sheet, means acting upon the long staple fibres 20 to attenuate them and embed the attenuated long staple fibres into the soft fibrous sheet to strengthen and impart stability to the latter, and means acting upon the combined sheet and long staple fibres as a unit to form superposed layers 25 thereof so that the long staple unspun fibres of one layer shall be at an angle to the long staple unspun fibres of the next adjacent layer in the production of the composite reenforced bat.

2. In a machine for making a composite reinforced cotton bat, the combination of a traveling conveyor for a fibrous cotton sheet, drawing and attenuating devices for relatively long staple reenforcing fibres constructed and arranged to progressively apply the attenuated 35 fibres to and impress them into the material of the fibrous cotton sheet as the latter is moved by the conveyor, and a camel back for feeding and reciprocating the combined cotton sheet and reenforcing fibres as a unit in the production of 40 superposed layers thereof to form the composite reinforced cotton bat.

3. In a machine for making a bat of fibrous material reenforced by longitudinally extending filaments, the combination of presser rolls, means 45 for feeding a sheet of soft fibrous material to the nip of the rolls, means for feeding longitudinally extending filaments to the nip of the presser roll to cause the longitudinally extending filaments to be embedded into the sheet of soft fibrous material as the two pass between the nip of the rolls together, a camel back mounted to swing about an axis below and adjacent to the presser rolls that it may receive the combined sheet of fibrous 50 material and reenforcing filaments, and a receiving conveyor to receive the fibrous material and reenforcing filaments transversely of itself.

4. In a machine for making a bat of fibrous material reenforced by longitudinally extending unspun fibres of long staple, the combination of presser rolls, means for feeding a sheet of soft fibrous material to the nip of the rolls, means for feeding longitudinally extending unspun 60 fibres to the nip of the presser rolls to cause the longitudinally extending fibres to be embedded into the sheet of soft fibrous material as the two pass between the nip of the rolls together, a camel back mounted to swing about an axis below and adjacent to the presser rolls that it may receive the combined sheet of fibrous material and reenforcing unspun fibres, and a receiving 65 conveyor to receive the fibrous material and reenforcing filaments transversely of itself.
